UNITED STATES PATENT OFFICE.

JOSEPH ROBINSON, OF MARYPORT, COUNTY OF CUMBERLAND, ENGLAND.

TIME-STRIKING WATCH.

SPECIFICATION forming part of Letters Patent No. 425,582, dated April 15, 1890.

Application filed February 10, 1887. Renewed September 16, 1889. Serial No. 323,996. (No model.) Patented in England October 18, 1886, No. 13,267, and in Canada May 1, 1887, No. 26,436.

To all whom it may concern:

Be it known that I, JOSEPH ROBINSON, a subject of the Queen of Great Britain, residing at Maryport, in the county of Cumberland, England, have invented certain new and useful Improvements in the Construction of Keyless Watches, (for which I have previously obtained Letters Patent in Great Britain, dated October 18, 1886, No. 13,267, and in Canada, dated May 1, 1887, No. 26,436,) of which the following is a full, clear, and exact description.

This invention has relation to watches of that class usually known as "stem-winders," and has for its object to provide a stem-winding watch by which the time will be indicated by means of a sounder or bell operated by means of the stem or winding apparatus of the watch.

This invention therefore consists in the construction, combination, and arrangement of parts, more fully described hereinafter, and specifically pointed out in the claims.

In the accompanying drawings, which illustrate my improvements as applied to that type of watches usually known as the "Waterbury" watch, Figure 1 is a plan view of a watch case and shank with striking-hammer attached in position to be operated directly from the winder. Fig. 2 is a side view of the same with a portion of the case broken away; Fig. 3, a view of the stem and attached pinion; Fig. 4, a view of the gong or bell. Fig. 5 is a view of a modification, in which the striker is operated by means of a pin or pins inserted in the face of the rear plate of the watch-movement; and Figs. 6, 7, 8, 9, and 10 are detail views.

In the class of watches herein described and illustrated the winding apparatus consists of a button H, attached to a shaft E, which carries a pinion C, which gears with teeth upon the periphery of the back winding-wheel A of the watch-movement, and, as will be seen, when the button H is rotated it will wind up the spring which is attached to the winding-wheel A.

In my proposed form of movement I construct the winding-wheel A with sixty teeth

upon its periphery and the gear C with twelve 50 teeth, so that five full turns of the button H will cause the winding-wheel A to revolve once; but I do not wish to confine myself to this exact construction, as I may vary the number of teeth upon the pinion C without 55 departing from my invention.

As will be understood by those who are familiar with the construction of this type of watches, the winding-wheel A makes a complete revolution each hour, and accordingly 60 in order to determine what length of time has elapsed since the watch has been wound up it is only necessary to ascertain how many full revolutions have been made by the winding-wheel A, and this I accomplish by the 65 following means: A pin B is attached to the face of the pinion C, and a hammer or striker D is pivoted within the case of the watch, its upper end e being in the line of the pin B and its lower end or head in position to strike 70 against the inner side of the case or on the bell J. At each complete revolution of the pinion C the hammer or striker will be raised by means of the pin B and caused to strike the case or bell J. As before described, if the pinion C has 75 twelve teeth and the winding-wheel A has sixty teeth, five strokes of the hammer will indicate a complete revolution of the winding-wheel A, and by counting the number of strokes of the hammer or striker one can correctly 80 determine the number of revolutions made by the winding-wheel A, and thus determine the length of time that has elapsed since the spring was wound up.

In the modifications illustrated in Figs. 5 85 to 10 of the drawings the pin by which the hammer is operated is placed upon the face of the winding-wheel A and the hammer end so placed as to be in the line of this pin. If but one pin be provided, each stroke of the 90 hammer will indicate a complete revolution of the winding-wheel A; but I may use two, three, four, or any desired number of pins. If, for instance, four pins be used, then each stroke of the hammer will indicate a quarter- 95 revolution, or fifteen minutes. If ten pins be used, each stroke will indicate a tenth of a revolution, or six minutes, &c.

In addition to the pins in the face of the winding-wheel A, I also provide a spring-dog F, working in the teeth of the winding-wheel A, which will indicate each separate tooth 5 wound up or each minute that has elapsed.

The operation is as follows: If it is desired to know the time without looking at the hands or dial, remember the time at which the watch was last wound. The stem is then turned, 10 and at each complete revolution of the winding-wheel A one hour is indicated as having elapsed, and as the wheel A has sixty teeth the number of clicks made by the spring-pawl F will indicate the number of minutes 15 in addition to the hour or hours as indicated by the strokes of the bell or gong, and by a simple mental calculation the correct time can be determined. Suppose, for instance, that the watch has been wound completely 20 up at ten p. m., and during the night it is desired to know the time. The watch is wound up, and at each complete revolution of the wheel A the bell or gong is sounded. In this case the gong strikes four times, indicating 25 thereby four revolutions of the wheel A, or four hours, as having elapsed. Then the click of the pawl F is counted to determine the minutes, and it sounds twenty times, thus indicating that four hours and twenty minutes 30 have passed since the watch was previously wound. By adding the four hours and twenty

minutes to ten p. m., the correct time, 2.20 a. m., is indicated.

Different intervals of time can be indicated by the different arrangements of the pins in 35 the wheel, as before described.

What I claim is—

1. The combination, with the winding mechanism of a time-piece, of a sounder operated through the medium of said winding mechanism, and thereby indicating the revolutions 40 of the winder, substantially as shown and described.

2. The combination, with the winding mechanism of a time-piece, of a sounder and a 45 pivoted striker and intermediate mechanism, substantially as shown and described, whereby each revolution of the winding mechanism will operate said striker one or more times, as set forth. 50

3. The combination, with winding-wheel A and its operating mechanism, of a pin or pins inserted in the face thereof, and striker D, having one end thereof in the path of said pins, whereby the revolutions of the plate 55 will operate the striker, substantially as shown and described.

JOSEPH ROBINSON.
